UNITED STATES PATENT OFFICE

97,531

DESIGN FOR A BASE FOR A RING OR SIMILAR ARTICLE

Thornton J. Manry, Kansas City, Mo.

Application August 1, 1935, Serial No. 57,908

Term of patent 7 years

To all whom it may concern:

Be it known that I, Thornton J. Manry, a citizen of the United States, residing at Kansas City, in the county of Jackson and State of Missouri, have invented a new, original, and ornamental Design for a Base for a Ring or Similar Article, of which the following is a specification, reference being had to the accompanying drawing, forming part thereof, in which,

Figure 1 is a perspective view of a base for a

ring or similar article, showing my new design.

Figure 2 is a side elevation of the base shown in Figure 1.

Figure 3 is a sectional view taken on the line 3—3 of Figure 2.

I claim:

The ornamental design for a base for a ring or similar article substantially as shown.

In testimony whereof, I affix my signature.

THORNTON J. MANRY.
